UNITED STATES PATENT OFFICE.

WILLIAM E. WOODARD, OF FOREST HILLS, NEW YORK.

LOCOMOTIVE ROD AND COUNTERBALANCE MECHANISM.

Application filed May 2, 1925. Serial No. 27,433.

To all whom it may concern:

Be it known that I, WILLIAM E. WOODARD, a citizen of the United States, residing at Forest Hills, in the county of Queens and State of New York, have invented certain new and useful Improvements in Locomotive Rod and Counterbalance Mechanism, of which the following is a specification.

This invention relates to locomotive rod and counterbalance mechanism, and its nature, objects, and advantages will be understood from the following.

In locomotive design it is customary to counterbalance the drivers for both rotating and reciprocating weights, and it is necessary to place the counterbalance inside the plane of the coupling rods. This means that the portion of the counterbalance which counteracts the reciprocating weight is approximately one foot inside the plane of the reciprocating parts. This in turn necessitates the employment of what is in reality an excess weight in the counterbalance, producing heavy dynamic augment, i. e., a proportionately great pressure on the rails when the force is downward and a proportionately greater lifting action on the wheels when the force is upward. Detrimental effects as to rail life and slippage follow.

In accordance with my invention, I propose to decrease the dynamic augment to a minimum, to thereby reduce the detrimental effects thereof.

How the foregoing, together with such other objects and advantages as may hereinafter appear, or are incident to my invention, are realized, is illustrated in preferred form in the accompanying drawings, wherein—

Fig. 1 is a side elevation of the drivers and the rods of a locomotive embodying my invention; and

Fig. 2 is a plan view of Fig. 1.

In the drawings, I have shown a locomotive having four sets of drivers, 1, 2, 3 and 4, although the invention is capable of other applications.

Driver 2 has what may be termed the main crank pin 5; driver No. 1 has a pin 6; and drivers Nos. 3 and 4 have crank pins 7 and 8.

Drivers Nos. 1 and 2 are coupled by a side rod 9, lying in a plane immediately adjacent the plane of the drivers. The main or connecting rod, indicated as a whole by the reference letter A, lies in a plane outside the

plane of the side rod 9. This main rod is of articulated construction but is unitary from an operative standpoint, and comprises the three members 10, 11 and 12. These members are respectively secured together, as by bushings 13 and 14 passing through the forked ends 14' and 15 of the members 10 and 11 respectively, and through the eye ends 16 and 17 of the members 11 and 12, respectively. Within the bushings 13 and 14 are floating bearing sleeves 18, as more fully set forth in my copending application, Serial No. 27,432, filed May 2nd, 1925. It will be seen bushings 13 and 14 form push and pull connections for the main rod parts, distributing the thrusts over the three pins 5, 7 and 8, and that the main rod parts lie in one plane, which is well out from the plane of drivers Nos. 3 and 4.

By this construction, I am enabled to counterbalance as follows: I equip drivers Nos. 1 and 2 with counterbalance weights 19, which weights provide for substantially only rotating balance and, therefore, are correspondingly small. I equip drivers Nos. 3 and 4 with counterbalance weights 20, which weights provide for both reciprocating and rotating balance. The weights 20 can be extended laterally very nearly to the plane of the main rod. In other words, the reciprocating balance is brought very close to the plane in which the reciprocating parts work, and the amount of weight provided for reciprocating balance can be cut down with the consequent decrease in the dynamic augment above referred to. The weights 20 may be of substantially the same cross-section as the weight 19 on the forward driver, the distance between the rear pair of drivers and the main rod being such that the desired amount of weight can be obtained by merely lengthening the weights.

It will, of course, be understood that the major part of the reciprocating weights, such as the cross-head, piston and piston rod, are not shown.

I claim:

1. The combination with a locomotive having more than two sets of drivers, a main crank pin on an intermediate driver, an articulated main rod coupled to said main pin and to the wheel or wheels to the rear of the wheel carrying such main pin, the parts of the main rod extending in the same vertical plane, rod means coupling the main pin carrying wheel to the wheel or wheels in

advance thereof, said means extending in a plane inside the plane of the main rod, a rotating counterbalance block on the wheel or wheels in advance of main crank pin carrying wheel, and a rotating and reciprocating counterbalance block on the wheel or wheels to the rear of said pin carrying wheels.

2. The combination with a locomotive having more than two sets of drivers, a main crank pin on an intermediate driver, an articulated main rod coupled to said main pin and to the wheel or wheels to the rear of the wheel carrying such main pin, the parts of the main rod extending in the same vertical plane, rod means coupling the main pin carrying wheel to the wheel or wheels in advance thereof, said means extending in a plane inside the plane of the main rod, a rotating counterbalance block on the wheel or wheels in advance of main crank pin carrying wheel, and a rotating and reciprocating counterbalance block on the wheel or wheels to the rear of said pin carrying wheel extended laterally outward to just short of the plane in which the main rod works.

3. The combination with a locomotive having more than two sets of drivers, a main crank pin on an intermediate driver, a main rod coupled to said pin and coupling rod

means extending rearwardly from said pin and lying in the same vertical plane as the main rod, coupling rod means extending forwardly from said pin and lying in a plane intermediate the wheels and the main rod, counterbalance means on the wheel or wheels in advance of said intermediate driver, and counterbalance means on the wheel or wheels to the rear of said driver carried laterally outward to just short of the plane in which the main rod works.

4. The combination with a locomotive having more than two sets of drivers, a main crank pin on an intermediate driver, a main rod coupled to said pin and coupling rod means extending forwardly from said pin and lying inside the plane of the main rod, and coupling rod means extending rearwardly from said pin and lying outside the plane of said forwardly extending rod means, counterbalance means on the wheel or wheels in advance of the said intermediate driver, and counterbalance means on the wheel or wheels to the rear of said intermediate driver carried laterally outward beyond the plane of said forwardly extending rod means.

In testimony whereof, I have hereunto signed my name.

WILLIAM E. WOODARD.
